(57) **CLAIM**

The ornamental design for a belt organizer, as shown and described.

DESCRIPTION

FIG. 1 is an isometric view of a belt organizer showing my new design;

FIG. 2 is a partial enlarged isometric view for a belt organizer according to the broken lines shown in FIG. 1; and,
FIG. 3 is a front elevational view of the belt organizer shown in an alternate configuration.

The broken lines shown represent unclaimed subject matter and form no part of the claimed design.
